ELECTROMAGNETICALLY OPERATED DEVICE

Gustav O. Wilms and Albert J. Dawe, Milwaukee, Wis., assignors to Allen-Bradley Company, Milwaukee, Wis., a corporation of Wisconsin

Application January 22, 1940, Serial No. 315,040

4 Claims. (Cl. 175—375)

This invention relates in general to electromagnetically operated devices suitable for the opening and closing of electric switches and the like, and in particular to a novel device employing an armature and a fieldpiece which may be electrically magnetized and demagnetized to cause engagement and disengagement in such manner that a part or all of the field and armature assembly functions alternatively as an electromagnet and as a demagnetizable permanent magnet.

One advantage of the apparatus of this invention is that it requires electrical energy only to effect engagement and disengagement between the armature and fieldpiece and, therefore, is an efficient device in that no energy is expended to maintain engagement of armature and fieldpiece.

Another advantage of the apparatus of this invention is that it is silent in operation in any stationary position and causes sound only when motion of the device is effected.

A further advantage of the apparatus of this invention is that it may be embodied in a structure of practically the same dimensions and cost as a comparative electromagnetically operated and maintained device.

These and other advantages, which will be apparent from the following description, are not possessed by switch-actuating apparatus heretofore known and used. In an effort to obtain the properties exhibited by the apparatus of this invention it has been customary in the art, prior to this invention, to employ a complicated, bulky and expensive system of locks and latches, none of which has been entirely satisfactory, or to employ permanent magnets in such a way that direct current only may be used to close the same.

To aid in the description of our invention reference is made to the accompanying drawings forming a part hereof wherein we have shown in Fig. 1 a front view of one form of electric switch embodying our invention, parts thereof being broken away and in section;

Fig. 2 is a wiring diagram of the electric switch shown in Fig. 1, with parts thereof in diagrammatic form;

Fig. 3 is a longitudinal view, partly in section, of Fig. 1 taken on the planes indicated by dotted line 3—3;

Fig. 4 is a detail view of the auxiliary lock-in switch indicated in general by numeral 31 in Fig. 3;

Fig. 5 is a detail view of the normally closed 53

auxiliary switch indicated in general by numeral 45 of Fig. 3;

Fig. 6 is a magnetic hysteresis curve; and

Fig. 7 is a magnetic hysteresis curve illustrative of the behavior of an electromagnet such as is employed with this invention correlated with a diagrammatic showing of the field strength and magnetic flux variations which are applied thereto to cause closing and opening of the switch in accordance with this invention.

Referring to the accompanying drawings, in which like numerals indicate like parts throughout the several views, the numeral 1 designates a flat sheet metal panel upon which the switch mechanism, designated generally as 2, and the electromagnetic actuating means, designated generally as 3, are mounted.

The switch mechanism 2, which may be of any form desired, is here shown as comprising two pairs of stationary contacts 4 adapted to be electrically bridged by the movable contact units 5, which are adapted for vertical movement in a manner similar to that shown in Patent Number 2,071,149 issued to Gustav O. Wilms et al., February 16, 1937. With a switch mechanism 2 of this form the stationary contacts 4 are secured to the top section 6 of the chamber 7, which chamber has a back section 8 and a front section 9. The back section 8 is secured to the metal panel 1 by two screws 10 and a mounting post 11, the latter being riveted to panel 1 and projecting outwardly through a slot 12 in a partition 13, which partition depends medially from top section 6.

Back section 8 is slotted to receive the rear of top section 6 and front section 9 is slotted to receive the front of top section 6, the whole being secured in place by means of mounting post 11, as shown.

The movable contacts 5 are mounted on posts 14, which are carried by a cross bar 15 of insulation material. Intermediate cross bar 15 and contact 5 is a spring 52, shown in broken line, which biases the contact 5 upwardly toward a shoulder 53 on post 14. The contact springs are each enclosed by a telescoping two part enclosure 16.

The electro-magnet designated in general by the numeral 3 comprises a U-shaped frame 17 riveted as shown to sheet metal panel number 1, a fieldpiece 18 secured to frame 17, an armature 19 of the form of an inverted T, and an energizing coil 20. The fieldpiece 18, which is of substantially inverted U-shape, is made up

of laminations 21 and in this instance are of silicon steel.

The armature 19 is composed of laminations 22, which in this instance are of a hardened tungsten steel alloy and have the property of comparatively high retentivity and high coercive force.

All of the laminations 22 are of inverted T form and extend as shown toward the adjacent surface 23 of the top portion of fieldpiece 18. The middle lamination of non-magnetic material designated by 24, however, extends beyond the other laminations through an opening in the top portion of fieldpiece 18 and has mounted thereon cross bar 15 by means of screw 25.

Middle lamination 24 is slotted as at 26 through which opening a screw 27 passes, which screw holds in place coil clamp 28 and armature guide 29. Coil clamp 28 secures coil 20 in position and is of spring material having an inwardly projecting portion positioned between the top portion of fieldpiece 18 and the top surface of coil 20. The armature guide 29 is passed through an opening in the bottom of the fieldpiece structure 18 and through the coil 20, serving to hold the coil against sidewise movement and as a guide for armature 19. The armature guide 29 has projecting portions extending adjacent to the top portion of the fieldpiece 18 that are engaged by the screw 27.

The lock-in switch designated generally by numeral 31 is shown in detail in Fig. 4 and comprises stationary contacts 32 and a movable bridging contact 33, a mounting post 34 for the movable contact, a spring 35, and an actuating bar 36 which is mounted as shown on an extension 37 from cross bar 15.

The normally closed auxiliary switch designated generally as by numeral 45 is shown in detail in Fig. 5 and comprises stationary contact 46, movable contact 47, movable contact spring 51, actuator assembly 48, biasing spring 49 and mounting block 50.

This type of auxiliary switch is described and claimed in the application of Lynn H. Matthias for "Auxiliary Switches for Electromagnetically Operated Devices," filed February 10, 1940, Serial Number 318,292, and assigned to the assignee of this application, which is the Allen-Bradley Company.

It is to be noted that the magnetic switch is shown in the closed position in Figures 1, 2 and 3. In such position of the magnetic switch, the lock-in switch 31 has its contacts closed and auxiliary switch 45 has its contacts open.

Spring 49 biases the actuator assembly 48 in the clockwise direction. With the armature 19 in the up or closed position, the actuator will, therefore, press the movable contact 47 downwardly out of engagement with contact 46. With the armature in the down or off position, the weight of the armature is sufficient to turn actuator 48 counterclockwise which allows contact 47, which is biased by means of spring 51, to close with contact 46.

If a piece of iron becomes magnetized by placing it in a unidirectional magnetic field and the magnetizing force be then removed, the iron does not become completely demagnetized. A certain magnetizing force of the opposite polarity must be applied to bring it back to its original condition. This phenomenon, where changes of flux lag behind the changes of magnetizing force, has been termed magnetic hysteresis. Because of magnetic hysteresis a B-H (flux density—

magnetizing force) curve taken with continuously increasing values of H to the maximum, and then with continuously decreasing values of H to a negative maximum, and so on, will assume the shape shown in Fig. 6.

The ordinate OC represents the retentivity, that is, the value of the residual magnetic flux density in the iron after the magnetizing force has been increased to its maximum and then removed. The abscissa OA represents the coercive force, that is, the value of the magnetizing force necessary to reduce the retentivity OC to zero.

Fig. 6 is a hysteresis curve plotted with magnetizing force H against flux density B and is representative of a piece of iron having a high retentivity and a high coercive force, whereas Fig. 7 shows a hysteresis curve plotted with magnetizing force H against total flux and is representative of the fieldpiece and armature, as used in this invention, in their closed position.

In the specific embodiment shown the alternating current flowing through the energizing coil 20 of the above described magnetic switch is proportional to the applied electromotive force. The energizing current, of course, lags the applied voltage or electro-motive force by an electrical angle depending upon the ratio of the coil's reactance to the coil's effective resistance.

The magnetizing force H is proportional to the magnetizing current, and any instantaneous value of H may be determined by projecting points of circle M onto the horizontal axis of Fig. 7. The circle M is described by a radius R proportional to the maximum value of the magnetizing current, and this radius or vector rotates with angular velocity equal to that of the magnetizing current. Actually, however, the figure as traced by the radius R is not a true circle, but rather an ellipse as R is slightly modified by the non-linearity of the magnetizing force vs. flux density relationship of the magnetic circuit. For purposes of simplification this is to be considered as a linear relationship in the following description.

In Fig. 7, ϕ is the total flux in the armature and fieldpiece when in the closed position.

The instantaneous values of ϕ are determined by projecting the instantaneous value of H onto the proper portion of the hysteresis curve.

It is to be noted that the instantaneous values of ϕ and of H are designated by the adding of sub numerals.

The convention is followed in Fig. 7 in that values of H to the left of the vertical axis are negative values, and that values of ϕ below the horizontal axis are negative values.

As the time increases from the instant corresponding to vector R at point J, moving counterclockwise to point K, the instantaneous values change from $H_2\phi=0$ to $H_4\phi_4$. After point L on the hysteresis curve has been reached and as the time increases, the instantaneous values of ϕ are determined by following the top of the loop as indicated by the arrow.

If, when H is a maximum, or at the instantaneous value of H_4 the magnetizing force is suddenly removed, the residual flux will have the particular value ϕ_2 as indicated on the hysteresis curve.

It is to be further understood that if the magnetizing force is removed at any instant from H_4 to $H=0$, after having reached the maximum value H_4 , the residual flux will always be equal

to ϕ_2 . This condition will also exist on the negative portion of the cycle, except that the residual flux will be $-\phi_2$ as indicated.

The magnetic switch as shown in Figures 1 and 3 requires a particular force to hold the contacts and other parts in the closed position. The flux corresponding to such a particular value is indicated in Figure 7 by the line *d* for a flux value of positive sign and line *d'* for a flux value of negative sign.

The lines *d* and *d'* thus define the minimum values of flux necessary for the armature and fieldpiece to remain in the closed position against the action of the opening bias which in the specific example disclosed is the weight of the armature and other associated parts plus the action of the various springs associated therewith. These lines also determine, as described below, the limits in electrical angle in which the armature and fieldpiece will not remain closed if *H* is removed.

The particular value $-H_1$ is the value of *H* that is just sufficient to reduce the residual flux ϕ_2 to a value ϕ_1 defined by the line *d*. The particular value $-H_3$ is the value of *H* that is just sufficient to yield after de-energization a residual flux $-\phi_1$ defined by the line *d'*. There are thus established two values of *H*, $-H_1$ and $-H_3$ that correspond to the set limits of switch closure *d* and *d'* respectively, and fix the angle α (alpha) in which the switch will not remain closed, upon de-energization of *H*, during one-half of the hysteresis cycle.

It is evident that twice the angle α in electrical degrees divided by 360 is equal to the fraction of a cycle during which, if the coil circuit is interrupted, the switch will not remain closed. In one particular device built in accordance with this invention, the possible period during which the switch will not remain closed constitutes 20% of a cycle. Such possible failure of the switch to remain closed, however, will be precluded as explained later on.

In order to open the switch, a sufficient alternating magnetizing force must be present to reduce the residual magnetism to some value less than ϕ_1 or $-\phi_1$. It is assumed in the particular example as shown in Fig. 7 that ϕ_2 or $-\phi_2$ is the maximum residual magnetism possible, and in this case, a slightly greater magnetizing force than $-H_1$ or H_1 will be sufficient to accomplish the opening. In order to assure the reduction of the maximum possible value of residual flux ϕ_2 or $-\phi_2$, it is then necessary that the $H-\phi$ relationship during energization of the drop out coil 20 have such values as shown by the small $H-\phi$ curve in dotted line in Fig. 7.

Referring to Fig. 2, which is a wiring diagram of the electric switch with parts thereof in dia-grammatic form, it is to be noted that the same is in the closed position. Conductors 60 and 61 are power feeder wires, each of which is connected to a stationary contact 4, and the movable contact units 5 being in closed position the circuit is completed through the other set of stationary contacts 4 to the conductors 62 and 63 leading to the load.

With the magnetic switch in the open position, auxiliary switch 31 open and auxiliary switch 45 closed, and the pilot start switch 70 closed, a circuit is completed from conductor 61, conductor 64, contacts of the start switch 70, conductor 65 through the contacts 46 and 47 of normally closed auxiliary switch 45, through the conductor 66 through a portion of energizing coil

20, through conductor 67 to power line 60. Thus coil 20 is energized to cause the armature 19 to move to the closed position. At substantially the closed position the magnetizing force *H* is a vector quantity, varying with the time and having a maximum value equal to H_4 as shown in Figure 7 and described above.

As the magnetic switch closes, it will be noted that contacts of the auxiliary switch 45 open, thereby breaking the closing energizing circuit and the switch will remain in the closed position providing the residual magnetism exceeds the opening bias. However, if the residual magnetism is insufficient and the switch does start to open the auxiliary contact closes again reapplying the closing magnetizing force to the switch and if the residual magnetism is then sufficient when the closing energizing circuit is open, the switch will remain in the closed position. The probability of the resulting residual magnetism being large enough is great since the ratio of the electrical angle over which the switch will not remain closed to that over which it will remain closed is small, and the necessity for several "tries" is remote.

The magnetic switch is so constructed that the closed position of the main switch contacts 4 and 5 overlap the operating position of the auxiliary switch 45 to such a degree that they do not open the main circuit in the event that the magnet makes several "tries" for a successful operation.

To open the magnetic switch, the pilot stop switch 71 is closed, whereby a circuit is completed from power conductor 61 through conductor 64, through contacts of stop switch 71, through conductor 68, through the contacts 32 and 33 of lock-in switch 31, through conductor 69, through all of coil 20, through conductor 67 and then to power conductor 60. The energizing coil 20 being so designed that with the utilization of the complete coil, the magnetic force *H* which is a vector quantity varying with time and having in this instance a maximum value slightly greater than H_1 reduces the residual magnetism to such a value that the switch opens. This is accomplished by increasing the number of turns of the opening coil as shown in Figure 2.

As described above, the closing circuit utilizes a portion of the coil and the opening circuit uses the complete coil.

In order to preclude the possibility of closing both the start and stop contacts simultaneously, which would cause the switch to "chatter," a mechanical interlock or other device should be included in the start and stop contact device to eliminate this possible condition.

In the description of the example of carrying our invention into practice, an electro-magnet of a straight line actuating motion is shown, however, other types of electromagnets may be employed such as the type that incorporates the pivotally mounted armature.

Our invention may be practiced with the same structure where direct current is used for securing magnetization i. e., to cause engagement of the fieldpiece and armature and to maintain the switch in the closed position by virtue of the residual magnetism derived from the closing energization. The opening of the switch can then be obtained by using A. C. as described above or by means of D. C. magnetizing force of opposite polarity from the residual magnetism and of such magnitude that the switch opens.

Further, our invention may be also used where

alternating current is used for magnetization and direct current of proper polarity is used to reduce the residual magnetism.

In every case, including the specific example as given in this specification, it should be understood that the reduction of the residual magnetism which causes the disengagement of the armature from the fieldpiece, is caused by a magnetizing force produced in the opposite direction to that of the residual magnetism. The magnitude of the magnetizing force which reduces the residual magnetism is determined by the method as shown in our disclosure, wherein the residual magnetism must be reduced to some value less than d or d' which is the value necessary to hold the parts in engagement.

The specific example herein disclosed may be considered a magnetic device wherein the armature 19 becomes a magnet on a temporary energization of the fieldpiece 18 by the coil 20, and wherein the fieldpiece after energization becomes a keeper; and on second temporary energization of the keeper or fieldpiece, the armature or magnet has its magnetism reduced to a value to permit disengagement of fieldpiece and armature. It is to be understood that armature or keeper is biased to the disengaged position.

In practicing the invention, it is only required that the magnetic circuit have such characteristics that the magnetizing force can create a residual flux that is greater than that necessary to keep the fieldpiece and armature engaged and that the demagnetizing force be sufficient to reduce the total magnetic flux to a value less than that necessary to keep the parts engaged.

While in accordance with the patent statutes we have disclosed the foregoing details of a specific embodiment of our invention, and while certain of the claims are directed to the details of this preferred embodiment, it is to be understood that the principles disclosed are capable of much wider adaptation to the art of magnetic devices generally. We desire, therefore, that the language of our claims shall be accorded the broadest reasonable construction, and that our invention shall be limited only by what is expressly stated therein and by the prior art.

We claim as our invention:

1. An electro-magnet device operable by alternating current comprising a magnetic circuit including a fieldpiece and an armature, an energizing winding for said fieldpiece, a finding switch in series with said energizing winding and a control switch in series with the finding switch and energizing winding for connecting the circuit of said energizing winding and said finding switch to a source of alternating current; said armature being biased from its closed position with the fieldpiece; said magnetic circuit, with armature and fieldpiece closed, capable of residual magnetism derived from energization of said winding by alternating current to provide a holding force sufficient to maintain said armature closed against said bias; said finding switch being under the control of said armature so as to be closed when the armature is in open position and to be open when the armature is in the closed position; whereby, said winding and said finding switch on being connected by said control switch to a proper source of alternating current causes the armature to move from open to closed position and if not retained in closed position then to move to open position and re-

peat the closing of said finding switch until said holding force is obtained greater than said bias.

2. An electro-magnet device operable by alternating current, comprising a magnetic circuit including a fieldpiece and an armature, an energizing winding for said fieldpiece, a finding switch in series with said energizing winding and a control switch in series with the finding switch and energizing winding for connecting the circuit of 10 said energizing winding and said finding switch to a source of alternating current; said armature being biased from its closed position with the fieldpiece; said magnetic circuit, with armature and fieldpiece closed, having sufficient coercive force and retentivity, whereby, a holding force greater than said bias is obtained from an alternating current magnetizing force upon de-energization at such a point on the alternating current cycle that the residual magnetism is 20 sufficient to develop said holding force; said finding switch being under the control of said armature so as to be closed when the armature is in open position and to be open when the armature is in closed position; whereby, said winding 25 and said finding switch on being connected by said control switch to a proper source of alternating current causes the armature to move from open to closed position and if not retained in closed position then to move to open position and repeat the closing of said finding switch until 30 said holding force is obtained greater than said bias.

3. An electro-magnet device operable by alternating current, comprising a magnetic circuit including a fieldpiece and an armature, an energizing winding for said fieldpiece, a finding switch in series with said energizing winding and a control switch in series with the finding switch and energizing winding for connecting the circuit of said energizing winding and said finding switch to a source of alternating current; said armature being biased from its closed position with the fieldpiece; said armature having high coercive force and high retentivity compared to said fieldpiece and said magnetic circuit, with armature and fieldpiece closed, capable of residual magnetism derived from energization of said winding by alternating current to provide a holding force sufficient to maintain said armature closed against said bias; said finding switch being under the control of said armature so as to be closed when the armature is in open position and to be open when the armature is in closed position; whereby, said winding and said finding switch on being connected by said control switch to a proper source of alternating current causes the armature to move from open to closed position and if not retained in closed position then to move to open position and repeat the 60 closing of said finding switch until said holding force is obtained greater than said bias.

4. An electro-magnet device operable by alternating current comprising a magnetic circuit including a fieldpiece and an armature, an energizing winding for said fieldpiece, a finding switch in series with said energizing winding, a control switch in series with the finding switch and energizing winding for connecting the circuit of said energizing winding and said finding switch to a source of alternating current, a de-energizing winding for said fieldpiece and a second control switch to connect the circuit of said de-energizing winding to a source of alternating current; said armature being biased from its

closed position with the fieldpiece; said magnetic circuit, with armature and fieldpiece closed, capable of residual magnetism derived from energization of said energizing winding by alternating current to provide a holding force sufficient to maintain said armature closed against said bias; said finding switch being under the control of said armature so as to be closed when the armature is in open position and to be open when the armature is in the closed position; whereby said energizing winding and said finding switch on being connected by said control switch to a

proper source of alternating current causes the armature to move from open to closed position and if not retained in closed position then to move to open position and repeat the closing of said finding switch until said holding force is greater than said bias and said second control switch on being closed causes said de-energizing winding to reduce the holding force to less than the said holding force to cause the armature to move to open position.

GUSTAV O. WILMS.
ALBERT J. DAWE.
